 Bergstein, trustees

Application May 17, 1941, Serial No. 393,892

4 Claims. (Cl. 229—31)

My invention relates to the general type of boxes known in the trade as "Automatic," which are shipped in flat knocked down form and readily erected prior to packing. It is a widespread practice at the present time to stitch or staple these types of boxes, and in my invention the cost and other attendant difficulties of the stitched or stapled box are eliminated, providing a superior product.

It is one object of my invention to provide an automatic overlap type of box that is adapted to high speed manufacture on existing folding and gluing machinery. Another object of my invention is to provide a process for the manufacture of this box in which there are no stitches or staples present, which is a particularly desirable feature of boxes which are used to pack garments and the like because the stitches and staples frequently cause tears in the fabric. Another object of my invention is producing boxes of this type with an extra end reenforcement to provide a better and stronger finished edge and an extra reenforcing end strip, to assure positive adhesion of the overlapping panel in a pressure conveyor, to provide a box with additional clearance space adjacent to the corner portions to facilitate the more ready assembly thereof. Other objects of my invention will become apparent as the description proceeds, reference being had to the claims hereinafter as to the nature and scope of my invention.

Now referring to the drawings:

Figure 1 shows a preferred type of flat cut and creased blank adapted to my invention.

Fig. 2 shows the first stage of folding.

Fig. 3 shows a succeeding stage in the folding.

Fig. 4 shows the final folding stage, illustrating the flat knocked down box in the position in which it is shipped to the user.

Fig. 5 shows the first step in the assembly of the box, one end having been partly raised toward the erect position.

Fig. 6 shows the finished erected box ready for receiving of the contents.

Fig. 7 is a view, somewhat diagrammatic, of a series of my folded blanks stacked in a conventional-type pressure stacker.

Fig. 8 is an enlarged cross sectional view of the end assembly of one of the boxes made according to the present invention. The section being taken on the plane of line 8—8 of Fig. 4.

Referring now to the blanks shown in Fig. 1, this could be made of any suitable semi-rigid or rigid material such as fibre board, cardboard, and the like. By line respectively of fold or

lines of cutting the blank is laid out to form indicated, having a main body panel A, opposite side walls B and B¹, opposite end walls C and C¹, and corner connecting sections divided by 5 diagonal lines of fold, the two portions of each corner of the corner connecting sections being designated as D and E or D¹ and E¹ as shown.

Articulated to the end walls C and C¹ are overlapping panels marked F and F¹ and articulated to the overlapping panels are auxiliary flanges marked respectively G and G¹.

Before proceeding with the description it might be well to clarify somewhat the use of the terms that will be followed herein. The terms, "end walls" and "side walls" are not intended to indicate proportions, as one may be longer than the other or vice versa, or they may be of equal length as in the case of a box that is square, but for purposes of simplicity in description the opposite pair of walls which has the articulated overlapping panels will be referred to as the "end walls," and the remaining pair of opposite walls will be referred to as the "side walls." The diagonal scored portions 15 which connect the side and end walls will be referred to as the "corner connecting sections," and the extra panel articulated to the overlapping panel will be referred to as the "auxiliary flange."

Now that the use of the terms has been clarified, I will describe my preferred folding and gluing operations in the fabrication of this blank into the finished automatic box.

The first stage of folding as indicated in Fig. 2, 35 consists of folding inwardly the side walls B and B¹, to overlie the main body panel A, and this same folding likewise folds inwardly the diagonally scored corner connecting sections, which thereupon overlie the corresponding end walls of the box, as shown in the drawings.

The next folding step indicated in Fig. 3, as indicated comprises the folding in of the auxiliary flanges G and G¹ to overlie the corresponding overlap panels F and F¹ as shown. If desired adhesive may be introduced between the meeting surfaces of these auxiliary flanges and the overlap panels to which they are articulated, prior to folding in the auxiliary flanges.

Before the final folding operation, which is shown in the next drawing, adhesive is introduced either on the surface of the auxiliary flange, or on the corresponding meeting surface of the end walls, and in Fig. 3, this adhesive area has been indicated by the stippled area on the surface of the auxiliary flanges, as shown.

Fig. 4 shows the succeeding and final stage of the preferred folding; the overlapping panels, with the previously infolded auxiliary flanges thereon, now being folded over, as indicated in Fig. 4, whereby the infolded auxiliary flanges lie between the infolded overlapping panels and the corresponding end walls. In this position pressure is applied to secure adhesion between these infolded auxiliary flanges and the corresponding end walls to secure the now folded box in the position indicated in Fig. 4.

When it is desired to erect the box for packing with the contents, the first step in setting the box up is as shown in Fig. 5, wherein as the side and end walls are brought into upright position, the corner connecting sections D^1 and E^1 double back upon themselves along the diagonal lines of the fold therein. As this is done the outer portions of the overlapping panel, that is, the portions of the overlapping panel F^1 which are not retained to the end wall by the auxiliary flange G^1 , are lifted over the shoulders of the corner connecting sections D^1 .

In Fig. 6, the finished erected box is pictured and it can be seen that the box is securely held in an upright position by the overlapping frictional engagement of the outer edges of the overlapping panel, resting over the shoulders of the folded corner connecting sections as mentioned above. It will also be apparent from this drawing and the previous ones that the assembly of the box is a simple and rapid matter, requiring the minimum of hand labor since there are no locks to fasten or tucks to engage, etc., but merely the raising of the side and end walls and the slipping of the outer portions of the overlapping panels over the edges of the corner connecting sections, and the box is retained in upright position, ready for use.

The process as described may be carried out on machines of the right angle type such as described in my U. S. Patent No. 2,149,111, and the earlier patents referred to therein. In the utilizing of this type of mechanism to carry out our process, the blank is first set in to the first angle of the machine with the side walls parallel with the direction of conveyance, and in the course of travel along the first angle the side walls and corner connecting sections are folded inwardly.

Thereafter, with the folds retained in folded position, the direction of motion is changed so that the blank thereafter travels parallel to the end walls. During this course of travel the auxiliary flanges are then first folded inwardly, the lines of articulation of such flanges being parallel to the direction of motion, and—with these folds retained in folded position—the overlapping panels are folded in to overlie the end walls, adhesive having been introduced to secure the auxiliary flanges to the end walls either prior to the folding of the auxiliary flange or if desired after the auxiliary flange has been folded but prior to the infolding of the overlapping panels.

As an alternative the process could be carried out by running the blanks through several untimed straight line gluing and folding machines; for example, the blanks could first be run through a straight line untimed gluing and folding machine which is only utilized for folding, i. e. to fold inwardly the two side walls and the corner connecting sections.

Thereafter the blanks with the side walls folded in could be taken from this machine and run through a second machine of a similar type, in the opposite direction to fold in the auxiliary

flanges and the overlapping panels. Since the auxiliary flange projects beyond the remainder of the blank a continuous stripe of glue from the standard type revolving adhesive applying wheel could be utilized, depositing this on the outer (or under) surface of the auxiliary flange prior to the folding in of the auxiliary flange and this second operation too could be on a continuous type machine, that is, without timing, having thereby high-speed operation. If desired, it would also be possible to fold in the auxiliary flanges as the first step, simply retaining it in folded position or adhering it down to the overlapping panel and thereafter carry out the succeeding steps of infolding the side walls and then the overlapping panels.

In any event, however, and whether carried out by hand or on one machine or several machines, in line with the several descriptions above, it is a requisite that the side walls be folded in prior to the infolding of the overlapping panels, and also that the auxiliary flange be folded in prior to the infolding of the overlapping panels, so that when the overlapping panels are folded inwardly the auxiliary flange lies sandwiched in between the infolded auxiliary panel and the corresponding end walls. It is also necessary to have adhesive applied before the final folding over of the infolded auxiliary flange upon the end wall, but the particular stage of the operation at which the adhesive is applied is immaterial as long as it meets the requirements as stated; and as previously mentioned—if desired—adhesive can also be utilized between the auxiliary flange and the overlapping panel, although this is not essential.

In Fig. 7, is illustrated somewhat diagrammatically, a series of my blanks in folded condition, in a conventional type dryer conveyor used in folding and gluing equipment. In said dryer conveyors or pressure stackers, the blanks are carried along in offset relation between slow moving yieldable pressure members or belts, to apply the necessary pressure and allow sufficient time for the adhesive to set or dry. With such a yieldable pressure arrangement, the pressure naturally is applied more heavily at the areas of greater thickness of the blank, and as can be seen from the illustration the extra thickness which the infolded auxiliary flange provides in my construction increases the pressure at this vital point and consequently assures positive and secure adhesion, and this feature is one of the advantages of my invention.

Fig. 8 is an enlarged cross sectional view of end assembly of one of the boxes made according to my invention, and here can be noted another important feature contributed by the auxiliary flange, namely, the fact that the auxiliary flange by spacing away the overlapping panel somewhat from the end wall, provides a tolerance or clearance space which permits the more ready assembly of the outer ends of the overlapping panel, over the corner connecting sections of the blank.

It can also be seen that the line of articulation of the auxiliary flange to the overlapping panel acts as a hinge, tending to prevent undue strain being thrown on the overlapping panel as the box is erected, resulting in a more satisfactory box because of less likelihood of tearing or injuring the overlapping panel during the course of raising the ends thereof over the infolded diagonal corner sections. This additional tolerance or clearance space, with the additional flexibility given by the hinged effect just mentioned,

are both important additional advantages of my invention.

It will be obvious that variations of the particular style of box from that illustrated, can be made, without departing from the features of my invention. The blanks illustrated for example can be used as a boat or tray, or a similar piece of a slightly larger size can be provided, to telescope over the piece shown for example, making a two-piece so-called full telescope style box. Or one of the side walls could have a lid panel with a tuck, making a one-piece box with a hinged tuck top lid, and these and other such variations are all contemplated within the scope of my invention.

It can also be noted that my invention as herein disclosed is well adapted to one piece telescope lid style boxes such as shown in my Patent No. 2,145,682. By providing the type of construction shown herein and carrying out the gluing and folding process as already described, on the type of equipment as already disclosed in my aforesaid Patent No. 2,145,682, a very useful and effective one piece telescope type cover box can be produced, either with or without the reinforcing strip for the back wall as desired, in a single operation.

It would likewise be apparent that variations can be made in the particular form of the cutting of the overlapping panel and auxiliary flange, if so desired. In the particular blank illustrated the outer edges of the overlapping panel are cut back somewhat as compared to the point at which the auxiliary flange is hinged, which I find helps facilitate the more ready assembly of the box. If desired, however, this edge of the overlapping panel could be straight instead of having cut-away portions, and the auxiliary flange hinged to it by a line of articulation along the central section thereof. Such variations are also included in the scope of my invention; having thus described my invention what I claim as new and desire to secure by Letters Patent, is:

1. A knocked down box having infolded side walls, outfolded end walls, overlapping panels articulated to said end walls, said overlapping panels being infolded, and auxiliary flange articulated to said overlapping panels, lying folded back under said infolded overlapping panels and adhesively secured to said end walls, said overlapping panels arranged to engage members on the side walls to maintain an erected condition of

said box when it is erected, and said auxiliary flanges being less in length than said overlapping panels and of such length as to lie between said side wall members.

- 5 2. A knocked down box having infolded side walls, outfolded end walls, overlapping panels articulated to said end walls, said overlapping panels being infolded, and auxiliary flanges articulated to said overlapping panels, lying folded back under said infolded overlapping panels and adhesively secured to said end walls, said overlapping panels arranged to engage members on the side walls to maintain an erected condition of said box when it is erected, and said auxiliary flanges being less in length than said overlapping panels and of such length as to lie between said side wall members, and said auxiliary flanges being also adhesively secured to said overlapping panels.
- 10 15 3. As an article of manufacture a knocked down box adapted to ready assembly comprising a cut and creased blank having a main body, and side walls and end walls with corner connecting sections having diagonal lines of fold therein, said end walls having overlapping panels articulated thereto, and auxiliary flanges articulated to said overlapping panels, said side walls being infolded to overlie said main body panel and said corner connecting sections being infolded to overlie the unfolded end walls, said overlapping panels being infolded to overlie said corner connecting sections and said end walls, and said auxiliary flanges being folded back under said infolded overlapping panels, and being of such limited length as to lie wholly between said corner connecting sections, and said auxiliary flanges being adhesively secured to said end walls.
- 20 25 30 35 4. In a knocked down box, an overlapping panel articulated to a wall and secured in folded position over said wall by a centrally located auxiliary flange of substantially lesser length articulated to said panel, folded under to lie between said wall and said panel and adhesively secured to said wall at least, said overlapping panel extending beyond said flange at its ends, and said flange acting to space said panel from said wall a sufficient distance to permit the exertion of effective pressure on said panel in producing said adhesive bond in spite of the location of box members between the ends of said panel and said wall.

SAMUEL BERGSTEIN.
